UNITED STATES PATENT OFFICE.

WILLIAM ZOPFF, OF DETROIT, MICHIGAN.

MUSIC-LEAF TURNER.

1,175,859.

Specification of Letters Patent. Patented Mar. 14, 1916.

Application filed June 29, 1915. Serial No. 37,025.

To all whom it may concern:

Be it known that I, WILLIAM ZOPFF, a subject of Emperor William II of Germany, residing at Detroit, in the county of Wayne 5 and State of Michigan, have invented new and useful Improvements in Music-Leaf Turners, of which the following is a specification.

The invention relates to a music leaf 10 turner, and has for its primary object to provide a novel construction wherein it will successively turn the leaves or sheets of music, and can be conveniently positioned upon a piano, organ, music stand, or the 15 like to support music, and is automatic in its action.

Another object of the invention is the provision of a music leaf turner of this character wherein a single member is operated 20 for the automatic turning of the music leaves in their order singly, thus obviating the necessity of handling the sheets for this purpose as is customary.

A further object of the invention is the 25 provision of a music leaf turner of this character which is simple in construction, thoroughly reliable and efficient in operation, strong, durable, and inexpensive in manufacture.

With these and other objects in view, the 30 invention consists in the construction, combination and arrangement of parts as will be hereinafter fully described, illustrated in the accompanying drawings, and pointed 35 out in the claims hereunto appended.

In the drawings:—Figure 1 is a front elevation of a music leaf turner constructed in accordance with the invention. Fig. 2 is an edge elevation. Fig. 3 is a similar view, 40 looking toward the opposite edge. Fig. 4 is a sectional view on the line 4—4 of Fig. 1. Fig. 5 is a sectional view on the line 5—5 of Fig. 1. Fig. 6 is a sectional view on the line 6—6 of Fig. 1.

Similar reference characters indicate corresponding parts throughout the several views in the drawings.

Referring to the drawings in detail, the 50 music leaf turner comprises a main support or board 10, preferably made from wood,

having secured to its rear face a lower transversely arranged rail 11, and an upper resilient hook member 12, both being designed to serve in the mounting of the music leaf turner upon the instrument or stand when 55 it is to be used for the turning of the leaves of music.

Fixed to the front face of the board 10 is a ledge 12 which serves as a rest for the music, while at an intermediate point on 60 the front face of the said board above and below the ledge 12 are substantially U-shaped bearings 13 which are arranged in longitudinal alignment and have journaled therein stud shafts 14 to which are fixed the 65 ends of swinging frames 15, each serving as a turning member for sheet music, and is preferably made from a single strand of stiff wire to give the requisite rigidity thereto, and these frames of the series vary in 70 size with respect to each other.

Coiled about one of the stud shafts 14 are a series of springs 16, one end of each being fixed to one limb of each frame, while the other end is secured in the bearing 13, and 75 these springs serve to move the arms from right to left for the automatic turning of the music leaf when the said frames are released, in a manner presently described.

Arranged centrally of the board 10 and 80 fixed beneath the uppermost bearing 13 and the lower ledge 12 is a resilient cord or band 17 which serves to hold the music in place upon the said ledge, while connected to the frames 15 are suitable members 18 for engaging the leaves of the music so as to assure the successful turning thereof when the frames are released.

Mounted at the lower edge of the board 10 is a boxing or housing 19 in which is 90 journaled a horizontally disposed roller 20, the shaft 21 of which is mounted in the sides of the boxing or housing 19 and has fixed thereto without the said boxing or housing ratchet wheels 22 and 23, respectively, while mounted upon the roller 20 are a series of trip projections 24, the same being arranged in staggered relation circumferentially of the said roller with respect to each other. Fixed to the boxing or hous- 100

ing 19 is a spring dog 25 which engages the teeth of the wheel 23 so as to lock the roller 20 against rotation in one direction, yet permitting it to be moved in the reverse direction.

Loosely connected with the shaft 21 next to the wheel 22 is an operating arm 26 on which is mounted a spring-held locking dog or pawl 27 which is adapted to engage the teeth of the wheel 22 for intermittently moving the roller 20 in one direction on the downward movement of the arm 26, while connected with the latter is a coiled retractile spring 28, the same being also connected to the board 10, and this spring serves to automatically lift the arm 26 after being pulled downwardly for the rotation of the roller.

Fixed at one side of the roller bearing 13 are spaced guide flanges 29 in which are mounted vertically slidable latch pins 30 which are adapted to engage in notches 31 formed in the lower limbs of the swinging frames 15 for locking the same at the right hand side of the music leaf turner, and between these flanges 29 and coiled about the pins 30 are expansion springs 32 which work against shoulders 33 formed on the said pins and serve to normally hold the same in locking engagement with the frames, the pins being extended below the housing or boxing 19 and terminate in finger grips 34 so that they can be manually actuated for releasing the frames if desired, or for the locking of the said frames when swung from left to right in their respective order.

The pins 30 are formed with projections 35 arranged in the path of movement of the trip projections 24 on the roller 20 so that when the roller is rotated the said trip projections 24 will engage the projections 35 on the pins for moving the same against the resistance of the springs 32 for the successive releasing of the frames 15, and thereby permit the turning of the leaves of the sheet music, which is effected by the frames under the tension of the springs 16 connected thereto.

Connected to the arm 26 is a pull cable or cord 36 which when pulled upon draws the said arm 26 downwardly, and in this movement it is locked with the ratchet wheel 26, thereby rotating the roller 20 a predetermined distance for the tripping of a single latch pin 30 to free the frame engaged thereby, and thus the latter will turn a single sheet of the music from right to left.

Mounted in the housing or boxing 19 is a guide bail 37 which serves to hold the pins 30 in close relation to the roller 20 so as to guide the said pins when being tripped by the projections 24 on the respective roller

and pins for the successful operation of the music leaf turner. When it is desired to turn the sheets of music from left to right the pins 30 are pulled downwardly out of the path of movement thereof, and when released will lock the frames 15 at the right hand side of the board 10 so that the leaves of music will be automatically turned from right to left when the music leaf turner is operated.

From the foregoing description, taken in connection with the accompanying drawing, the construction and manner of operation of the device will be clearly understood, and therefore a more extended explanation has been omitted.

What is claimed is:—

1. A music leaf turner comprising a support, a plurality of frames swingingly mounted thereon, a plurality of locking pins supported for engagement with the frames to hold the same against swinging movement, springs acting upon the frames for the swinging thereof when released by the pins, a roller having tripping projections engageable with the pins to successively release the same on rotation of the said roller, means for imparting rotary movement to the roller, means for locking the roller against reverse rotation, means for guiding the pins during movement thereof, and a mounting for the roller and pins and connected with the support.

2. A music leaf turner comprising a support, a plurality of frames swingingly mounted thereon, a plurality of locking pins supported for engagement with the frames to hold the same against swinging movement, springs acting upon the frames for the swinging thereof when released by the pins, a roller having tripping projections engageable with the pins to successively release the same on rotation of the said roller, means for imparting rotary movement to the roller, means for locking the roller against reverse rotation, means for guiding the pins during movement thereof, a mounting for the roller and pins and connected with the support, and means for moving the operating means to normal position subsequent to the rotation of the roller.

3. A music leaf turner comprising a support, a plurality of frames swingingly mounted thereon, a plurality of locking pins supported for engagement with the frames to hold the same against swinging movement, springs acting upon the frames for the swinging thereof when released by the pins, a roller having tripping projections engageable with the pins to successively release the same on rotation of the said roller, means for imparting rotary movement to the roller, means for locking the roller against reverse rotation, means for guiding

the pins during movement thereof, a mounting for the roller and pins and connected with the support, means for moving the operating means to normal position subsequent to the rotation of the roller, and means for moving the pins into locking relation to the frames.

In testimony whereof I affix my signature in presence of two witnesses.

WILLIAM ZOPFF.
